MULTIPLEX PATTERN

Application filed March 12, 1928. Serial No. 260,917.

The invention relates to combination patterns for dresses and other clothing, an object of which is to provide in one set of patterns two or more designs of dresses or wearing apparel.

Such patterns may be made of any durable material that is adapted to be used innumerable times.

Another object is economy to the buyer in that one pattern may be made to serve the purpose of several patterns.

An advantage of this invention is that when one has succeeded in procuring a perfect fitting pattern, a number of variations may be incorporated without danger of changing the fit of said pattern.

An object is to provide a pattern of such construction and arrangement that such garments may be cut by a novice without confusion.

Other objects, advantages and features of invention may appear from the accompanying drawing, the subjoined detailed description, and the appended claim.

The accompanying drawing illustrates the invention.

Figure 1 represents, on a small scale, a pattern for the front of a dress.

Fig. 2 is a pattern for the back of said dress.

Fig. 3 is a sleeve pattern for said dress.

The accompanying drawings represent two styles of dress, style A being a loose, unfitted dress with kimono sleeves and in which the 35 perforations are ignored; style B represents a close-fitting dress of the princess type in which the sleeve pattern C is used.

Figs. 1 and 2 show but one-half of the front and back patterns 1 and 2, respectively, the front and back margins 3 and 3' being placed on lengthwise folds of the goods.

Each half pattern 1 and 2 is formed with bottom margins as a, a' , that are at right angles respectively as at $a'', a''',$ to the front 45 and back margins 3, 3' that extend in straight

lines from the bottom margins a, a' , to the neck notches b, b' , and the shoulder margins 11 and 12 extend in straight lines downwardly aslant relative to the sleeve end margins c, c' which extend downwardly toward side 50 margins d, d' ; and curved under-arm margins e, e' respectively join the margins c to d and c' to d' . Each of the half patterns is provided with arm scye markings as at 14, 15 between the arm end margins c, c' and the 55 neck notches b, b' . The front half pattern is provided with close fitting garment markings 5" extending from the bottom margin a to the arm scye marking 14 to which it is connected at the close fit arm scye point f, f' 60 that is practically on a level with the loose fit under-arm point g ; and cutting lines indicated by the markings 18 extend from the side margins d and d' to the under-arm scye points f and f' respectively.

Style A is the simplest form, requiring but two pieces to make the dress aside from trimmings and accessories, while the style B requires 8 pieces, viz., one front 4, two side fronts 5, one back 6, two side backs 7 and 65 two sleeve pieces C aside from trimmings and accessories. Either type of sleeve 8 or 9 may be used. The type 8, being loose about the wrist, may be gathered onto a band or cuff, not shown.

To cut the princess type of dress the patterns 1, 2 will be laid upon the folded goods, margins 3 and 3' being placed upon lengthwise folds of the goods; markings will then be made along the lines of circular perforations 10 to indicate the lines for cutting. If desired, seams may be allowed outside the markings 10, in which case the pattern will be removed when the parts 5 and 6 are cut, and the markings will then indicate the lines 85 on which the seams are to be stitched and a margin sufficient for the seam be allowed on each perforated line marking 10. The pattern will then be replaced on the goods for the markings for side fronts 5 and side 90

backs 7, being careful to allow seam margins beyond the lines of perforations 10, and the cutting is done as before described. The seams are then stitched or basted, joining the edges 4' of the front to the edges 5' of the side fronts, and in like manner the edges 6' of the back to the edges 7' of the side back, likewise the edges 5" and 7" making the under arm seam. The front 1 will be joined to the back 2 at the shoulders 11 and 12. The sleeves 8 or 9, which are cut in like manner to the pieces before described, will have their seams 8' or 9' closed and will then be inserted in the arm scye, the edges 13 of the sleeve being sewed to the edges 14 and 15.

The slotted lines 16 and 17 are waist and hip lines, respectively, and may be used in different ways. A blouse may be fashioned from style A pattern by cutting the goods at line 17, and may be provided with sleeves by cutting at lines 14, 15 and 18, thus forming the necessary arm scye in which to sew the sleeves.

A skirt may be formed from the lower halves of either styles A or B by cutting at the line 16.

A jacket may be designed by using the same pattern as for the blouse and cutting it away at the front at line 19 for a jacket meeting only at the throat, or at 20 for a jacket with a more open throat or front, and either kimono or set-in sleeves may be used.

Also an "Eton" or shorter jacket may be made by following the above directions for jackets and cutting at the waist line 16 instead of at the hip line 17.

The various lines of perforations may be marked in a variety of colors, a different color for each style or type, thus to distinguish one from the other, or perforations of different shape may be used, as the circle, triangle or slot, as illustrated at 4', 20 or 16.

The patterns are preferably formed of a tough paper to make them more durable. Various other modifications may be employed without departing from the spirit of my invention, but the foregoing described styles are deemed sufficient illustration.

I claim:

50 A loose fit and close fit dress pattern comprising two pieces each having a straight bottom margin, a straight edge margin, at right angles to the bottom margin, a neck notch at the top of the straight edge margin and a straight shoulder and arm top margin extending aslant downwardly from the top of the neck notch, an arm end margin at substantially right angles to the shoulder and arm top margin, a straight side seam margin extending from the bottom margin toward the arm end margin, and a curved under-arm margin tangent to the side seam margin and connecting such side-seam margin and the arm end margin, and forming an under arm scye point at the lower end of the end

arm margin; said pattern pieces being also provided with markings outlining a close fit dress comprising a curved side seam marking line and a curved arm scye marking line uniting at an under arm scye point at substantially the level of the corner formed by the junction of the side seam margin and the arm end margin of the pattern piece.

In testimony whereof, I have hereunto set my hand at Los Angeles, California, this 1st day of March, 1928.

BEATRICE TELIS.
